UNITED STATES PATENT OFFICE.

BENJAMIN PRICE, CHARLES W. E. MARSH, AND RICHARD LABOURNE,
OF NEWPORT, ENGLAND.

TUBE-ROLLING MILL.

SPECIFICATION forming part of Letters Patent No. 608,908, dated August 9, 1898.

Application filed December 13, 1897. Serial No. 661,704. (No model.)

To all whom it may concern:

Be it known that we, BENJAMIN PRICE, engineer, residing at Brentburn, Corporation road, Newport, and CHARLES WILLIAM EARLE MARSH and RICHARD LABOURNE, civil engineers, residing at Newport, county of Monmouth, England, subjects of the Queen of Great Britain, have invented certain new and useful Improvements in Apparatus for Rolling Metal Tubes from Hollow Ingots, of which the following is a specification.

This invention has for its object improvements in or relating to the process of and apparatus for swaging or rolling metal tubes by reducing and extending hollow ingots or mandrels such as described in specification forming part of United States Patent No. 570,816, dated November 3, 1896.

This invention consists, mainly, in a new or improved method and means for controlling the movements of the housing-rolls, cams, or swaging devices, mandrel, and ingot placed thereon.

We use throughout the following description the same letters of reference to indicate the parts in all the figures of the drawings where like parts are shown, in order, as far as possible, to avoid needless repetition in describing the various modifications shown.

Figure 1 represents a side elevation, partly in section, showing an apparatus for rolling tubes from hollow ingots according to our present invention. Fig. 2 represents a plan view of the apparatus shown in Fig. 1. Fig. 3 is an enlarged side elevation, partly in section, showing a modified arrangement of devices for rotating and advancing the mandrel. Fig. 4 is a sectional elevation of the parts shown in Fig. 3, taken at right angles to the view shown in Fig. 3. Fig. 5 is a detail side elevation of another modified arrangement of devices for rotating and advancing the mandrel, wherein rocking mechanism is substituted for the chain and gear shown in Figs. 3 and 4 for rotating the screw. Fig. 6 is a view taken at right angles to the view shown in Fig. 5. Fig. 7 is a side elevation illustrating a further modification of our apparatus. Fig. 8 is an end elevation of the apparatus shown in Fig. 7, as seen from the right in said figure. Fig. 9 is a top plan view

of the apparatus shown in Figs. 7 and 8. Fig. 10 represents a modified form of device for holding the mandrel, which may be substituted for the cotter shown for that purpose 55 in the preceding figures. Fig. 11 is an end view, slightly reduced, of the parts shown in Fig. 10, as seen from the left in said figure. Fig. 12 represents a detail view of a modification of our apparatus in which a piston 60 working in a cylinder is shown for operating the roll-housing. Fig. 13 represents a further modification in which a piston is used for operating the roll-housing. Fig. 14 represents a still further modification in which 65 a crank-pin and sliding block are used, and Fig. 15 is a detail elevation illustrating a device for governing the extent of turn given to the mandrel.

In the apparatus shown in Figs. 1 and 2 the 70 main crank-shaft M is journaled in the base H' and has motion imparted to it by suitable gearing or driving mechanism. The said main crank-shaft M transmits, as hereinafter described, the necessary movements to the rolls 75 R R, mandrel O, and ingot W for the purpose of extending the short thick hollow ingot into a long tube of the desired size and thickness of wall in one passage between the operating-rolls, between which it remains the whole 80 time. When the rollers R R are at their extreme backward position—that is, nearest the feed mechanism—the space formed between them—i. e., the gap or opening—is at its largest size. At this point the forward 85 end of the ingot W (which has previously been made with a hole of a suitable diameter) is introduced between the rolls R R on the forward stroke of the housing N, which is accomplished by the aforesaid main crank-shaft 90 M by means of the connecting-rod H², operated by the crank-pin M², the rocker N², pivoted at N^X, and the links or pitmen N'. The rolls R R turn on their axes, and the grooves therein, which are the operating portions, act 95 on the ingot W and considerably reduce and extend it.

The rollers for carrying out this process have portions of their peripheries for the operative parts, while the other portions, made 100 with a smaller radius, constitute the enlarged space or gap for advancing and turning the

ingot W with the mandrel O. To bring the rolls into one and the same position on coming in contact with the ingot, we mount pins S S on the shafts of the rollers R R, which 5 roll upon toothed racks H H, secured to the base H'.

Although we prefer securing the racks H H to the base H', they may in some cases be given a reciprocating motion either opposite 10 to or in the same direction as the rollers R R.

The feed and turning mechanism consists of a disk M', with a cam-groove in its periphery, which governs the advance and turning movements of the mandrel O and ingot W 15 periodically—i. e., intermittently—through the cam-operated pin P' by means of intermediate link P, ratchet D², shaft D, sprocket or chain wheel D', the endless chain C, the sleeve A', and the screw-spindle A.

20 The boss L of the saddle B has a screw-thread cut to receive the screw A. The sleeve A' is provided with a feather or key adapted to slide in a long groove or keyway a running longitudinally of the screw-spindle A, so as

25 to allow the said spindle to slide either forward or backward through the sleeve A', and thus the partial revolution of the sleeve A' will cause the screw-spindle A to rotate, and as a result to advance or retire through the

30 boss L of the saddle B, according to the direction of revolution of the said sleeve. The saddle B is capable of sliding to and fro on the bed B' for the purpose of immediately adjusting and introducing the forward end 35 of the ingot W between the operating-surfaces of the rolls R R without the intervention of the screw-spindle A; but this is only done before the commencement of the operation, and the saddle B may then be clamped

40 or firmly fixed to the bed B' by any suitable means. After the first attack of the rolls upon the ingot the pawl of the ratchet D² is put in gear and imparts motion to the shaft D, sprocket-wheel D', through the endless 45 chain C, sleeve A', the screw-spindle A, and therefore the mandrel O, with the ingot W.

For the purpose of moving the saddle B into any desired position on the bed B' the shaft D has a keyway d cut from one end to the 50 other, and in which a feather or key d', secured in the sprocket-wheel D', slides. By this means it is immaterial in what position the saddle B may be on the bed B'. The screw-spindle A will always be capable of receiving motion from the shaft D. The shaft D projects through the bed B' at C² for the 55 purpose of placing a handle or key thereon to turn the screw-spindle A back after the hollow ingot or tube has been extended to the 60 desired size. This of course can only be done when the pawl of the ratchet D² is out of gear. The shaft D is then free to revolve in either direction.

The mandrel O is connected to the feed-screw spindle A by a cotter l; but it may be secured in any other desirable manner. For instance, it may be screwed into the sleeve.

Figs. 3 and 4 show a modification of the feeding and turning mechanism in which a faced ratchet or clutch D^x is mounted upon the screw-spindle A and the shaft D is oscillated around its axis, whereas in the arrangement shown in Figs. 1 and 2 the said shaft D is given a succession of intermittent movements always in the same direction 70 about its axis. The movement of the screw-spindle is effected by the faced ratchet or clutch D^x, which has a key of feather a' sliding in the groove a, formed lengthwise in the screw-spindle A, as seen in Fig. 4. The 75 ratchet or clutch D^x is thrown out of action by the lever Y and leaves the sleeve A' free to turn either way about the screw A, the sleeve A' in this connection having no key or feather, but being free to turn to and fro 80 freely on the screw-spindle A without imparting any motion thereto when not in engagement with said ratchet D^x. When, however, the said ratchet D^x is forced against the serrated face of the sleeve A' by the coiled 85 spring V, motion is given to the screw-spindle, as above described.

Figs. 5 and 6 show an arrangement in which the chain C shown in the preceding figures is replaced by a link P², which may be connected to a rocking lever (not shown) on the shaft D. (Seen in Figs. 3 and 4.) This link P² is shown as pivotally connected to a rocking frame D⁴, carrying a pawl V^x, pressed upon by a spring V, the said pawl engaging 95 the peripheral teeth on a ratchet-wheel D⁵, which latter incloses the shaft A and is provided with a feather or key d³, which engages in the longitudinal groove or keyway a in the said shaft, as seen in Fig. 6. V³ is a 100 lever by means of which the pawl V^x is released from the ratchet-wheel D⁵.

In all the examples shown the swaging devices or rollers advantageously have their grooves formed with a concentric portion in 110 combination with an abrupt enlarged groove, or they may be eccentric grooves—that is to say, gradually widening and deepening at their operative portions. They may also be other than regular in their eccentricity—that 115 is, the breadth and depth of said grooves may first quickly diminish for a short length and then very gradually diminish for a prolonged portion of their length. The section of the groove may also be circular, oval, or otherwise 120 formed for the purpose of shaping the tube into any desired form.

In Figs. 7, 8, and 9 we show further modifications of a feeding and turning gear. The cam-disk M' is mounted on a counter-shaft 125 M⁰, which is driven from the main crank-shaft M. This disk has two working grooves, one in its periphery for turning and the other in its face for advancing the mandrel and ingot. The mandrel, upon which the ingot has advantageously been previously placed, is held in the sleeve by a cotter l. When the swaging devices pass over the ingot on the mandrel O, the sleeve A', in which the mandrel

is supported, is by means of the cam-groove in the face of the disk M' and levers P⁴ and O' moved back. This result is obtained because the cotter l is not driven through the mandrel O, but at its side only, merely forcing it against the side of the hole formed in the sleeve A' for its reception, leaving the mandrel O, with the ingot, held by and between the swaging devices. The mandrel is sufficiently secured by means of the cotter to prevent its being moved by the action of the rolls on the ingot.

When the return stroke of the housing N is completed, the cam-groove in the face of the disk M' is again in action and moves the sleeve A', with the mandrel and its ingot, (which is now liberated,) a suitable distance forward, (the ingot being sufficiently compressed on the mandrel as to enable this being done,) and at the same time rotates them by means of the cam-groove in the periphery of disk M' and levers N³, P², and A² advantageously through an angle of ninety degrees to cause the lateral fins formed on the ingot to be removed during the next operation of the rolls. The sleeve A' has a keyway which slides over a key secured to the lever A² to allow for the forward-and-backward motion of the said sleeve in the support B, the feed forward of the mandrel and ingot being such that a portion of the latter is operated upon during the previous forward stroke together with a fresh portion being treated each time.

The device shown in Fig. 10 is applicable for holding the mandrel in the sleeve instead of the cotter already described. It forms a reliable means of seizing the mandrel to advance and turn it. The two grips O³ O³ are pivoted in the sleeve A' and have a coiled spring O² pressing against them at one side. The pressure is capable of adjustment by the cap O¹, which compresses or opens the spring O² by means of the screw-thread cut in the sleeve A' and upon which the cap O¹ is mounted. When the sleeve A' is brought back, the two grips O³ O³ open out and release the mandrel O, which is held between the rolls with its ingot; but on the forward stroke the grips O³ O³ immediately seize the mandrel and carry it forward, the ingot, with its mandrel, at this moment being liberated from the rolls R R for this purpose.

Although we have described two grips only, it is evident that three or more may be usefully adopted, and other means may be employed for effecting this particular motion of the mandrel and ingot. The feed forward of the ingot is thus effected when it is released by the rolls, so that the ingot and its mandrel may be freely moved forward, and the return movement of the sleeve is effected when the ingot and mandrel are pressed by the rolls, and as a result the mandrel, with the ingot, passes farther and farther through the rolls. As shown in Fig. 12, the housing N, carrying the rolls R R, may be worked to and fro by a piston-rod working in the cylinder G.

In Fig. 13 an oscillating cylinder G is journaled in the base H', the bracket J being secured to the base H', so that the piston-rod pin T describes a curved path, as shown, this piston-rod pin T being linked to the housing N by the link N' and to the bracket J by the link N³, these links N' N³ thus forming a toggle.

In Fig. 14 a quick return motion is effected by the crank-pin, (on the crank-shaft M,) with the slide-block T' sliding to and fro in the suitably-shaped slot of the rocker N'. In all the examples hereinbefore described and illustrated the rollers are moved bodily over the tube and at the same time are revolved around their axes.

Fig. 16 shows a still further modification of a device for governing the quarter-turn of the ingot W. The rope C², which is wound round the cylinder D³, has a weight attached to it that it may exert a pulling force always in the direction of the arrow 4. The cylinder D³ is part of the ratchet D⁴. The feed-screw A passes through the ratchet D⁴, a feather or key d⁴ on the latter engaging in the longitudinal groove or keyway a in said shaft. The escapement-movement device P⁶ is pivoted upon the pin T⁸ and is rocked to and fro at predetermined intervals in the direction of the arrows 5 6. The pawls V³ V⁴ serve to govern the extent of rotation of the ratchet D⁴. One of these pawls is always in gear. To insure that the pawls will not go back to the same recess, they are provided with the springs K³ K⁴.

Other means may obviously be employed to accomplish, as described, the movements of the housing, ingot, mandrel, and swaging devices without departure from the essential features of this invention, and the described arrangements are therefore only intended as examples for carrying out the present invention. For instance, the cylinders G or main crank-shaft M may be arranged to reciprocate the housing direct without the intervention of the rocker N', and the rolls may be controlled in their rotative movements by links jointed at both ends—one end to a crank secured to the shaft of the swaging devices and the opposite end to the base or fixed frame of the machine, as shown in Figs. 15 to 17 of the said Patent No. 570,816—or suitable guides or slots with sliding blocks may be advantageously adopted. The swaging devices may be journaled or mounted in the housing or bearings, with their shafts or axes on which they turn in a vertical line or any other desirable position. If the shafts are dispensed with, the swaging devices may be pivoted or carried in the housing in any other suitable manner. They may also be actuated and the position of the grooves controlled and maintained in the same relative positions on coming in contact with the ingot, as well as through the entire operation, by using suitable guides or fixed slotted links, and in the slots of these links pins (which are fixed near the peripheries of the swaging devices) are

mounted with sliding blocks, so that with the reciprocating movements of the swaging devices the pins, with their blocks, describe a to-and-fro motion in the suitably-shaped slots 5 of the links.

What we claim, and desire to secure by Letters Patent of the United States, is—

1. In an apparatus for the manufacture of metal tubes from hollow ingots, the combination with a supporting-base; a reciprocating roll-housing mounted thereon; a rocking beam pivotally connected at one end to said reciprocating roll-housing; means for imparting a rocking motion to said beam; swaging-rolls rotatably mounted in said housing; pinions fixed upon the axes of said rolls; and toothed racks fixed upon the supporting-base with which said pinions engage and thereby cause the rotation of said rolls as said housing is reciprocated; of a mandrel for holding the ingot; a support for said mandrel; and means for intermittently advancing and turning said mandrel, substantially as described.

2. In an apparatus for the manufacture of metal tubes from hollow ingots, the combination with a supporting-base; a reciprocating roll-housing mounted thereon; a rocking beam pivotally connected to said reciprocating roll-housing; means for imparting a rocking motion to said rocking beam; a transverse shaft journaled in said supporting-base; means for rotating said shaft; and a cam-disk mounted upon said shaft to rotate therewith; of a mandrel for holding the ingots; a support for said mandrel; and devices for intermittently rotating and intermittently advancing said mandrel operated by said cam-disk, substantially as described.

3. In an apparatus for the manufacture of metal tubes from hollow ingots, the combination with a supporting-base; a reciprocating roll-housing mounted thereon; a rocking beam pivotally mounted upon said supporting-base and pivotally connected to said reciprocating roll-housing; means for imparting a rocking motion to said beam; swaging-rolls rotatably mounted in said housing; pinions fixed upon the axes of said roll; and toothed racks fixed upon said supporting-base and meshing with said pinions; of a transverse shaft journaled in said supporting-base; means for rotating said shaft; a cam-disk mounted upon said shaft to rotate therewith; a mandrel for holding the ingot; a support for said mandrel; and devices for intermittently rotating and intermittently advancing said mandrel operated by said cam-disk, substantially as described.

4. In an apparatus for the manufacture of metal tubes from hollow ingots, the combination with a supporting-base; a reciprocating roll-housing mounted thereon; a rocking beam pivotally mounted upon said supporting-base and pivotally connected to said reciprocating roll-housing; means for imparting a rocking motion to said beam; swaging-rolls rotatably mounted in said housing; pinions

fixed upon the axes of said rolls; and toothed racks rigidly mounted upon said supporting-base and meshing with said pinions; of a mandrel for holding the ingots; a support for said mandrel, a rotary shaft mounted transversely in said supporting-base; a disk having a cam-groove in its periphery mounted upon said shaft; a link, and a pin connected thereto adapted to follow the cam-groove in said disk; mechanism connected with said mandrel for imparting an intermittent partial rotary movement thereto operated by said link and pin actuated by said cam-disk, and means for intermittently advancing said mandrel, substantially as described.

5. In an apparatus for the manufacture of metal tubes from hollow ingots, the combination with a supporting-base; a reciprocating roll-housing mounted thereon; a rocking beam pivotally mounted upon said supporting-base and pivotally connected to said reciprocating roll-housing; a driving-shaft mounted transverse of said supporting-base and having a crank thereon connected to said rocking beam; a counter-shaft driven from said driving-shaft and having a cam-disk mounted thereon to rotate therewith; swaging-rolls rotatably mounted in said housing; pinions fixed upon the axes of said rolls; and toothed racks rigidly mounted upon said supporting-base and meshing with said pinions; of a mandrel for holding the ingot; a support for said mandrel; mechanism connected with said mandrel and operated by the rotation of said cam-disk, for imparting an intermittent partial rotary motion to said mandrel; and mechanism also operated by the rotation of said cam-disk for intermittently advancing said mandrel, substantially as described.

6. In an apparatus for the manufacture of metal tubes from hollow ingots, the combination with a supporting-base; a reciprocating roll-housing mounted thereon; a rocking beam pivotally mounted upon said supporting-base and pivotally connected to said reciprocating roll-housing; means for imparting a rocking motion to said beam; swaging-rolls rotatably mounted in said housing; pinions fixed upon the axes of said rolls; and toothed racks rigidly mounted upon said supporting-base and meshing with said pinions; of a mandrel for holding the ingots; a support for said mandrel; a rotary shaft mounted transversely in said supporting-base; a disk having peripheral and facial cam-grooves therein mounted upon said shaft to rotate therewith; devices arranged to follow one of the grooves in said disk, and mechanism operated thereby for imparting an intermittent movement to said mandrel; and devices arranged to follow the other groove in said disk, and mechanism operated thereby for intermittently advancing the mandrel, substantially as described.

7. In an apparatus for the manufacture of metal tubes from hollow ingots, the combination with a supporting-base; a roll-housing

mounted thereon; and means for causing the rotation of said rolls in said housing; of a mandrel for holding the ingots while being operated upon by said rolls; a support for 5 said mandrel; means for intermittently rotating said mandrel in said support; and a device for intermittently advancing the mandrel, arranged to seize and to release the mandrel at predetermined intervals as the latter 10 is advanced, substantially as described.

8. In an apparatus for the manufacture of metal tubes from hollow ingots, the combination with a mandrel for holding the ingots; and means for intermittently rotating said

mandrel; of a sleeve for inclosing the mandrel; pivoted jaws mounted within said sleeve, and arranged to grip the mandrel when said sleeve is moved in one direction and to release the mandrel when moved in the opposite direction; and means for imparting a reciprocating movement to said sleeve, substantially as described. 15 20
